UNITED STATES PATENT OFFICE.

MELVILLE C. BRAGDON, OF NEWTON HIGHLANDS, MASSACHUSETTS.

SIGNAL APPARATUS FOR RAILWAYS.

SPECIFICATION forming part of Letters Patent No. 244,430, dated July 19, 1881.

Application filed May 14, 1881. (No model.)

To all whom it may concern:

Be it known that I, MELVILLE C. BRAGDON, of Newton Highlands, of the county of Middlesex and State of Massachusetts, have 5 invented a new and useful Improvement in Signal Apparatus for Railways; and I do hereby declare the same to be described in the following specification and represented in the accompanying drawings, of which—

10 Figure 1 is a rear elevation, Fig. 2 a top view, Fig. 3 a side elevation, Fig. 4 a longitudinal section, and Fig. 5 a transverse section, of an apparatus embodying my invention, the nature of which is set forth in the claims 15 hereinafter presented. Fig. 6 is a front view of the plate N, to be described.

This apparatus relates to what is known as the "block signaling system," and is to give notice to a car or train approaching a station 20 whether the section of track between it and the next succeeding station is clear of any train or car. The stations are generally to be a mile apart. On the car passing a station the danger-signal will be made by the red 25 target of the apparatus being thrown down to cover the opening of its standard. At the same time the danger-signal of the station next in rear will be thrown up or off its standard-opening, so as to uncover the latter and 30 indicate that the track between the two stations is clear.

In the drawings, A denotes a lever, fulcrumed to a short post, B, and having a helical spring, C, arranged under its shorter arm and to bear 35 such upward. The said shorter arm is supposed to be so arranged relatively to the railway-track as to be passed over by the wheels of one side of a car or train while such car or train may be passing the station at which such 40 lever may be situated. At the end of its longer arm the lever has a toothed sector, a, to engage with a gear, b, fixed on a tubular shaft, f, that turns on the driving-arbor c of a train, D, of gears, the last one of which has to its arbor 45 d one or more fans or vanes, e, to so act against the atmosphere while the arbor may be in revolution as to retard the running down of the train of gearing. A ratchet-wheel, g, fixed 50 on the shaft f alongside of the first gear, h, of the train, connects with the latter gear by one or more pawls, i, such being so that on the

longer arm of the lever A rising upward the tubular shaft will be revolved backward so as to disconnect the ratchet and first gear of the train, the force of the operative spring of the 55 lever causing the train D to be set in motion. Thus when a car may pass across the lever the gear b and the ratchet will be turned backward in consequence of the movement which will be given to the lever, the spring being 60 free to move the lever and train D on the car leaving the lever.

Alongside or near the retarding-train D is a standard, F, having a round hole, l, made through it at its upper part. A target, G, is 65 to so operate with this hole as either to cover or uncover it, such target being supported by an arm, m, extending from a tubular shaft, n, arranged to turn on a stud or journal, o, projecting from the standard. A weighted or 70 heavy arm, q, is extended down from the shaft n, and serves to revolve the shaft so as to throw the target toward and over the opening of the standard.

From a stud, r, projecting from the shaft n, 75 a rod, s, extends to and is fixed to the center of the flexible head t of a drum, H. From the said drum a conduit or pipe, u, is led to the station next in advance of that at which the apparatus may be placed, and is to open 80 into or communicate with the suction-drum of the signaling apparatus at such advance station, each station having a like signal apparatus, the suction-drum of that shown in the drawings being represented at I. This drum 85 I consists of an inverted hollow cylinder, v, having a flexible head or diaphragm, w, from the center of which a rod, x, extends downward through a helical spring, w', and a shelf, x', to which the spring is fastened at its lower 90 end. At its upper end the spring is secured to the diaphragm w, and by its contractile power operates to draw the diaphragm downward. The drum I is supported by a frame, K, across which the shelf x' extends. At its 95 foot the rod x is stepped upon the longer arm of a lever, L, whose shorter arm projects underneath and against the longer arm of the lever A.

A knee-lever, M, fulcrumed to the standard F, and arranged as shown, has its shorter arm 100 extended into a recess in the longer arm of the

lever A, or is so connected with the said arm of the said lever A as to be movable therewith and by it. The upper arm of the lever M carries a spring-hook, y, to engage with a stud, z, projecting from the tubular shaft n. Furthermore, there may be extended from the standard a plate, N, having a hole, a', in it. (See Fig. 6.) A curved target, O, carried by an arm, b', projecting from the main target, is arranged back of the plate N, as shown. That face of the target O which is next the plate N is to be painted red. The auxiliary target O moves with and is moved by the main target, so as to cover and uncover the hole a'. The perforated plate N and the extra target O are to serve as additional means of notifying the conductor of a car or train, should he have not properly noticed the main target before passing the station, as the auxiliary target may be seen by him while at and passing the station.

The operation of the signal apparatus may be thus described: A car, on crossing the shorter arm of the lever A, will depress it so as to cause the longer arm of such lever to move upward. At the same time the actuating-spring C will be contracted. While the longer arm of the lever A is rising upward the toothed sector a will turn the gear b backward, whereby the ratchet-wheel g will be similarly revolved backward. The knee-lever M will in the meantime be moved toward the standard F, so as to carry its spring-hook y off the stud z. The targets, by the gravitating power of the weighted or heavy arm q, will then be moved so as to cover their respective holes in the standard F and plate N, thus showing "danger" to an approaching train, the arm q bringing

up against the bracket d', through which the upper arm of the lever M extends. The spring C, being free to act against the lever A, will next cause the longer arm of the said lever to move downward, its descent being retarded by the gear-train and its fans. As the targets fall forward their tubular shaft n will turn on its journal, and by means of the rod s will lift at its middle part the diaphragm or flexible head t of the drum H. In descending the longer arm of the lever A will depress the shorter arm of the levers L and M, and thereby move the said levers. The longer arm of the lever M will move in a direction away from the standard, so as to carry the spring-hook y to

a position to catch upon the stud z, when the targets are next thrown back, such hook, by catching upon the stud, serving with the stud to hold the targets back or off their holes until the time may come for such target to fall forward and cover the holes of the standard F and the plate N. While the lever L is being moved by the downward movement of the long arm of lever A the diaphragm w of the drum I will be forced upward; but while the lever A may be moved by a car in passing over it the said diaphragm will be drawn down-

ward by the contractile force of the spring, such spring having been expanded by the forcing of the diaphragm upward by the lever L acting against the rod encompassed by the spring. On the diaphragm being thus pulled downward, air in the drum I will be rarefied, and as a consequence the air in the drum H at the station next in rear will be correspondingly rarefied, whereby the pressure of the atmosphere upon the flexible head of such drum will depress the said head, and thereby, through the rod connecting it with the tubular shaft of the targets, turn said shaft so as to throw the targets back off their openings of the standard F and plate N. On the lever M being moved so as to carry its longer arm toward the standard F, the spring-hook y will be moved off the stud z, so as to enable the weighted arm q to act and move its target or targets to "danger." While the targets are being drawn back to safety, the stud z will be carried against the spring-hook, which, under the pressure, will give way and slip over and catch on the stud, so as to hold the target from moving to "danger" until the proper time for it to do so.

The retarding train of gears and its fans as applied to the lever A are to cause the longer arm of the said lever to fall gradually and not too suddenly, in order for the drum I to effect the proper rarefaction of the air in the conduit to the drum H of the back station.

From the above it will be seen that on a car or train of cars passing one station having the signal apparatus the target or targets thereof will be thrown down to "danger," to indicate that the car or train has left the station, and on reaching or passing the next station with its signal apparatus the target or targets of the latter apparatus will be thrown down to "danger" and those of the station in rear will be thrown to "safety," so as to indicate that the track between the two stations is clear.

By having to the target G the supporting tubular shaft n and the stud z, and by having the knee-lever M and its spring-hook y combined therewith and with the lever A and its spring C, should either of these latter parts become damaged or broken, the knee-lever would generally, if not always, move so as to carry its spring-hook off the stud z, in which case the target would move to indicate "danger." The knee-lever, if desired, may be provided with an overbalance-weight, W, arranged on an arm, f', projecting from such lever, as shown.

What I claim as my invention is as follows:

1. The combination, substantially as described, for operating the signal target or targets, as set forth, it consisting of the spring C, lever A, toothed sector a, gear b, shaft f, ratchet-wheel g, pawl i, retarding-train D, levers L M, air-rarefying drum I, spring w', rod x, conduit u, auxiliary drum H, rod s, shaft n, stud z, spring-hook y, and weighted arm q, all adapted and arranged substantially as set forth.

2. The combination of the auxiliary target

O and its perforated plate N, applied to the standard F and main target G, as described, with such main target G and its operative mechanism, substantially as set forth, consisting of the spring C, lever A, toothed sector a, gear b, shaft f, ratchet-wheel g, pawl i, retarding-train D, levers L M, air-rarefying drum I, spring w', rod x, conduit u, auxiliary drum H, rod s, shaft n, stud z, spring-hook y, and weighted arm q, combined, arranged, and adapted to operate essentially as set forth.

3. The combination of the target G and its

supporting-shaft n, provided with the stud z, with the knee-lever M and its spring-hook y, and the lever A and its spring C, all being applied and for use substantially as set forth.

4. The combination of the spring C, lever A, toothed sector a, gear b, shaft f, notched wheel g, pawl i, and the retarding-train D, as set forth.

MELVILLE C. BRAGDON.
